UNITED STATES PATENT OFFICE.

EDISON BROCK, OF CHICAGO, ILLINOIS.

SOIL CAN.

Application filed May 20, 1926. Serial No. 110,320.

My invention relates to soil cans for use in connection with passenger cars, and a novel construction or device for supporting the same.

5 The object of the invention is to provide a novel and simple construction of soil cans having means for quickly applying the same in supporting position and which can be easily transported or carried, as well as 10 arranged to occupy a minimum of space upon a truck, and to overcome the objections to previous devices in this respect by avoiding fixed projections extending from the can which often render it difficult to handle the 15 can and to properly support it beneath the hopper chutes of various types of cars.

Other and further objects of the invention will be apparent as the description proceeds.

In the accompanying drawing:—

20 Fig. 1 is a side elevation, partly in section, of the novel soil can supported in position for use.

Fig. 2 is a front elevation, and

25 Fig. 3 is an enlarged fragmentary view taken on the line 3—3 of Fig. 1 with the bail in an upright or vertical position.

In the illustrated embodiment, the can is designated at 4 and may be provided with the usual reinforced rim 5 forming a bead 30 encasing a wire 6, if desired. Pivoted to the can at its upper edge at diametrically opposite points is a handle forming a bail 7 preferably of channel metal as shown, being produced from a strip bent in U-shape form. 35 This U-shaped member is inverted and pivoted to opposite sides of the can, as at 8, in any suitable way so that the bent end will be disposed uppermost or at one side of the pivots while the ends 9 forming the legs of the U-shaped member or bail extend straight 40 or rectilinearly on opposite sides of the can and in spaced parallel relation thereto in a downward direction, and are preferably longer.

45 Preferably, the pivot is in the form of a bolt or rivet engaged through apertures in the legs of the bail at diametrically opposite sides of the can together with an interposed spacing sleeve or nut 10 and a strip 11 of galvanized iron or the like, suitably soldered 50 or riveted to the can to reinforce and stiffen the same at the points of pivotal connection of the bail therewith. A suitable lock nut 12 is mounted on the inner end of each pivot.

55 Also provided on the handle at the center

of the closed or bight portion thereof is a short chain section 13, preferably having four links for a purpose to be hereinafter more fully set forth. Near the bottom of the can 60 on one side midway between the sides of the bail and the pivots, a drop handle 14 is provided which is pivoted beneath an offset portion 15 of a strap 16 suitably riveted or otherwise fastened to the can, as clearly 65 shown in Figs. 1 and 2 of the drawings.

In illustrating the application of the device, I have shown in Fig. 1 a fragmentary portion of a passenger car including the truck, and platform, as well as the relation 70 location of the latter to the truck, in which the floor of the car is designated generally at 17 and the side of the car at 18, while the truck frame is designated at 19, the wheel at 20 bearing on the track rail 21 supported 75 by the ties 22 of the concrete or other bed structure 23, which in stations is usually provided with an elevated platform 24 between the tracks at the sides of the cars. The usual hopper 25 is provided with a chute 26 80 leading beneath the same from the bottom or floor of the car and extending outwardly at a slight angle above but outwardly of the truck frame 19. Usually it is difficult to apply the cans in common use, in supporting 85 position, as well as to remove the same, and oftentimes the can will not be properly supported beneath the chute or can only be arranged beneath the same with considerable difficulty in different types of cars. They are 90 usually provided with fixed projections or supporting means which do not permit compensation for variation in the relation of the truck frame, chute, and side of the car, and much difficulty is experienced in applying 95 the cans. Moreover, the fixed projections on the can take up considerable space on trucks in transporting.

The present invention overcomes these objections and in use the can is disposed beneath the chute 26 with the extremities of the legs or sides 9 extending over and resting on top of the truck frame 19, as shown in Fig. 1 of the drawings. The bail 7 is then engaged over a hook 27 provided on 100 the side of the car in a downwardly extending position with the bill of the hook extending inwardly. Owing to the bail being pivoted to the can, it will properly compensate for different relations in the positions 105 of the truck frame, chute, and hook to each other. In some cases, it is necessary or de-

sirable to employ the chain 13 for engaging the hook 27 where the space between the truck frame and the hook is greater or for temporarily suspending the can. The application and removal of the can is facilitated by grasping the handle 14 in addition to the bail 7, and when the bail is in the position shown in Fig. 2 with the handle 14 flattened against the side of the can, the device will 10 occupy a minimum of space, so that a maximum number of the cans can be arranged upon a hand-truck or the like for transportation.

The hook 27 is commonly installed as a 15 part of the car for the purpose of supporting soil cans, water cans for hot bearings, etc. This hook is standard with the Pullman cars and sleeping cars of roads running their own sleeping car service. The hook is 20 commonly installed in location as shown for supporting soil cans and for other purposes.

Some cans now in use are provided with 25 fixed projections. In addition to the objections to such projection above pointed out, there is also the objection that the relative height of hook, spout, and truck frame in various cars varies due to design, wheel wear, etc. The fixed projection does not adapt itself to such variations while the 30 present soil can support automatically adjusts itself, the can remaining in a vertical position due to gravity.

Most cans in use are of a type which hang 35 by one or two bails from the hook in position as shown without other means of support, except in certain cases a contracted neck or top intended to engage around the spout from the car. As the spouts vary in size, angle, and inclination, length beneath 40 car floor, and position with reference to hook, it is not practical with much equipment now in use to design a can which will readily adapt itself so as to engage with the spouts of the various cars.

Where cans are supported by one or two bails from the hook as the principal means of support, since the spout is at a considerable distance in a horizontal line from the hook, it becomes necessary to make the can 50 of an unusual or complicated shape or to make it unnecessarily large, particularly in depth so that the center of gravity will be at a great enough distance beneath the hook and spout to allow the can to hang from the 55 hook and the top to swing over so as to be under the spout. This is objectionable, as such large cans are unsightly and due to the imperfect method of support the lower portion of the can often swings out beyond the 60 side of the car so as to form an obstruction, and be very objectionable to passengers.

The present soil can and its novel method of support is such that it readily adapts 65 itself to the hook in its standard position with a further support upon the truck frame,

both of which with the arrangement as provided serve to support the can midway between the hook and the truck so as to hang freely by gravity directly under the spout. The chain provides further adjustment where 70 equipment is encountered with very large spouts or with them not in proper position with reference to hook location. The can thus supported hangs close to the truck and due to this and its proper size is not unsightly and does not extend beyond the side 75 of the car.

It is intended that the cans may be handled in a closed top rectangular body hand truck of size such as to take eight or ten cans. It is, therefore, important that the can be without projections and not unreasonably large. The can is very simple in construction, yet of such shape as to have the greatest 85 strength, and the cost of material and labor is a minimum. An objection to a fixed projection on cans is that it also becomes a hazard or at least an annoyance to passengers should the can be momentarily set upon the passenger platform. 90

While I have shown and described my invention in a preferred form, I am aware that various modifications and changes may be made without departing from the principles of the invention, the scope of which can be 95 determined by reference to the appended claims.

I claim as my invention:

1. A soil can comprising a can proper and a bail mounted in fixed pivoted relation on the can having extended supporting portions terminating short of the bottom of the can. 100
2. A soil can comprising a can proper and a bail fixedly pivoted to the can and having rectilinear extensions beyond the pivots. 105
3. A soil can comprising in combination with the can proper, a U-shaped bail pivoted to opposite sides of the can and having legs extending along said sides beyond the pivots in a direction opposite to the bight portion 110 of the bail.
4. A soil can, a U-shaped bail pivoted at diametrically opposite sides of the can and having legs extending beyond the pivots and spaced apart a distance greater than the diameter of the can throughout their lengths, and a foldable handle mounted on one side of the can near its bottom intermediately of the pivots. 115
5. A soil can, a U-shaped bail pivoted at diametrically opposite sides of the can and having legs extending beyond the pivots, a flexible supporting member on the bight portion of the bail, and a drop handle on one side of the can at right angles to the pivots, the bail or flexible connection being adapted 120 to engage a support on the side of a car and the legs adapted to rest on the truck frame of the car. 125
6. The combination with a car having a 130

truck frame, a hook beneath the side of the car and a hopper chute extending downwardly from the car floor and outwardly of the truck frame; of a can having a bail 5 pivoted thereto with extended sides to engage over the truck frame and its bight portion adapted to engage the hook.

7. The combination with a car having a truck frame, a hook beneath the side of the car and a hopper chute extending downwardly from the car floor and outwardly of the truck frame; of a can having a bail 10 pivoted thereto with extended sides to engage over the truck frame and its bight portion adapted to engage the hook, and a small 15 handle on the can intermediately between the sides of the bail.

8. The combination with a car having a truck frame, a hook beneath the side of the car and a hopper chute extending downwardly from the car floor and outwardly of the truck frame; of a can having a bail 20 pivoted thereto with extended sides to engage over the truck frame and its bight portion adapted to engage the hook, a small 25 handle on the can intermediately between the sides of the bail, and a short chain on the bight portion of the bail.

9. A soil can comprising a receptacle and supporting member thereon mounted to take 30 a position projecting from opposite sides thereof to engage spaced supports such as a car truck and a hook extending down from the side of the car body.

10. A can of the class described, comprising 35 a receptacle and a bail on the can adapted to take a position projecting from opposite sides thereof to rest upon the truck frame of a car, and a support at the side of the car body with the can in a vertical position beneath a spout.

11. The combination with a car having a truck frame, and a hopper chute extending downwardly from the car floor; of a can having a bail pivoted thereto with extended 40 straight sides to engage over the truck frame and its bight portion adapted to be supported at one side of the car body or floor.

12. A soil can of the class described, having 45 means to support the same beneath a car 50 hopper chute, said means adapted to rest on or engage the truck frame, and supporting or suspending means arranged at the side of the car.
